[57] CLAIM

The ornamental design for a surface-mountable razor holder, as shown and described.

DESCRIPTION

FIG. 1 is a perspective view of a surface-mountable razor holder showing my new design therefor;

FIG. 2 is a front elevational view. The broken line drawing representing a razor is for purposes of illustration only and forms no part of my design;

FIG. 3 is a rear elevational view. The broken line drawing representing a razor is for purposes of illustration only and forms no part of my design;

FIG. 4 is a right side elevational view, the left side elevational view being a mirror image thereof;

FIG. 5 is a top plan view; and,

FIG. 6 is a bottom plan view.
